[57] CLAIM

The ornamental design for a pocket level, as shown and described.

DESCRIPTION

FIG. 1 is an isometric view of a pocket level incorporating my new design;

FIG. 2 is a right side elevation view thereof, the left side elevation view being a mirror image;

FIG. 3 is a rear end elevation view thereof;

FIG. 4 is a front end elevation view thereof;

FIG. 5 is a top plan view thereof;

FIG. 6 is a bottom plan view thereof;

FIG. 7 is a right side elevation view of an alternative embodiment of a pocket level incorporating my new design; and,

FIG. 8 is a front end elevation view thereof.

All views not shown in the second embodiment being identical to those shown in FIGS. 1, 3, 5 and 6.

1 Claim, 2 Drawing Sheets
